WRISTWATCH

Gaston Vuilleumier, Le Landeron, Switzerland, assignor
to Ebauches Electroniques S.A., Marin, Neuchatel,
Switzerland

Filed Feb. 18, 1971, Ser. No. 116,749

Claims priority, application Switzerland Sept. 14, 1970

Term of patent 14 years

Int. Cl. D10—02

U.S. Cl. D42—8

FIG.1

FIG.2

FIG.3

FIG.4

FIG.5

FIG.6

FIG. 1 is a top plan view of a wristwatch embodying
my new design;

FIG. 2 is a bottom plan view;

FIG. 3 is a front elevational view;

FIG. 4 is a rear elevational view;

FIG. 5 is a side elevational view; and

FIG. 6 is a perspective view thereof.

The side opposite that shown in FIG. 5 is a mirror
image of the side shown.

The broken lines showing portions of a wristwatch
strap and time indicating numerals are for illustrative
purposes only.

I claim:

The ornamental design for a wristwatch, substantially
as shown and described.
